UNITED STATES PATENT OFFICE.

ANDREAS LANGE, OF SCHÖNINGEN, NEAR HELMSTEDT, GERMANY.

TRACK.

1,196,958.

Specification of Letters Patent. Patented Sept. 5, 1916.

Application filed January 27, 1915. Serial No. 4,651.

To all whom it may concern:

Be it known that I, ANDREAS LANGE, a citizen of the German Empire, and resident of Schöningen, near Helmstedt, Germany, have invented certain new and useful Improvements in Tracks, of which the following is a specification.

My invention relates to improvements in tracks, and more particularly in tracks which consist of a plurality of rails located one beside the other and adapted to be shifted laterally together with the sleepers or cross-ties supporting the same. Tracks of this class are used for example in connection with dredging machines and their cars, and in this case the tracks are gradually shifted laterally of the direction of the movement of the machines as the work of the latter proceeds, and such shifting is effected either by hand or by special machines. It has generally been found to be a considerable inconvenience, that by shifting the tracks the rails which are secured to sleepers of considerable length are loosened, so that after shifting the tracks the rails must be secured again to the sleepers, and that the sleepers are destroyed after a short time. These objections are serious because for fixing the rails to the cross-ties a large number of workmen is necessary, if the operation of the dredging machine can not be interrupted for a considerable time, and because the cost of the sleepers is high.

The object of the improvements is to provide a track of this class in which these objections are removed.

With this object in view my invention consists in providing a track in which only a part of the rails are rigidly secured to the cross-ties, while the other rails are loosely supported on the ties, the loose rails being held at the proper distance from the fixed rails by being connected therewith and with one another by transverse connecting members, the fixed rails and transverse connecting members providing a rigid frame to which the rails are secured and which is connected with the sleepers only by the fixed rails.

This construction is advantageous also for this reason that for shifting the tracks the machine or the workmen have to support only a part of the weight of the section of the track which is being shifted to-

gether with the cross-ties, because only the 55 rails which are loosely supported on the cross-ties are lifted, while the cross-ties slide with their ends on the ground. Therefore the power required for shifting the track is reduced, and furthermore the cross-ties are subject to less strain, because the power for shifting the tracks is transmitted to the loose rails through the transverse connecting members and not through the cross-ties. 60 65

For the purpose of explaining the invention an example embodying the same has been shown in the accompanying drawings, in which the same letters of reference have been used in all the views to indicate corresponding parts. 70

In said drawings—Figure 1, is an end view of a dredging machine and a car mounted on the track, Fig. 2, is a cross-section of the track, Fig. 3, is a plan view of 75 a section of the track, Fig. 4, is a detail view showing the joint of a pair of rails, and Fig. 5, is a cross-section similar to that shown in Fig. 2 and illustrating in an exaggerated way the position of a cross-tie 80 and the rails mounted thereon in the state of being lifted.

In the drawings I have illustrated the invention in a track which is used in connection with a dredging machine. But I wish 85 it to be understood, that my invention is not limited to such use.

As shown a dredging machine 1 runs on rails 2, 3, 4, the rail 4 being provided for supporting the part of the dredging machine which is termed the tender 5. The soil which has been taken up by the scoops or buckets 6 of the machine is fed into conveying cars 7 which run on rails 8 and 9 disposed between the rails 3 and 4. All the 90 rails 2, 3, 4, 8, and 9 are supported on cross-ties 10 which are common to all the rails. 95

In tracks of the old construction all the rails are secured to the cross-ties 10 as rigidly as possible. But in my improved track 100 only the rails 8 and 9 on which the cars 7 run are rigidly secured to the cross-ties. These rails are secured in the usual way by means of hooked plates 11 and 12 which are secured to the cross-ties by means of bolts 105 13 and 14 passing through the cross-ties. The other rails 2, 3, and 4 are loosely supported on the cross-ties. For holding the

rails at their proper distances from one another, I employ transverse connecting members 15, 16, and 17 similar to the spacing bars or gage bars the use of which is well known in connection with the two rails of ordinary tracks in the example shown in the drawings these connecting members consist of angle irons. The rails 4 are secured to the transverse member 17 by means of 5 two clamping plates 18 which are bolted to the member 17. The rails 8 and 9 are connected with the member 16 by clamping plates 19 and 20, and the rail 3 is secured to the member 15 by means of a clamping plate 10 10 21 and a clamping brace plate 22 which engages with its other end over the inner base portion of the rail 2. At the outside of the said rail a bracket 23 is provided which is particularly strong and which is made in a 15 preferred embodiment of the invention of angle iron. This bracket assures the connection between the rail 2 and the member 15, and simultaneously it provides a support for the rail 2 which is subject in the 20 operation of the dredging machine, to the most heavy strain. The member 16 is connected with the members 15 and 17, by plates 24 and 25 respectively connected to the respective members by bolts and nuts 25 30 and in such a way, as to permit of a slight flexibility of the frame consisting of the parts 15, 16, and 17, for which purpose the nuts of the bolts are made more or less loose. The rails 2 and 3 which provide more particularly the track for the dredging machine proper can be secured in relative position by 35 means of cross-members 26 disposed between consecutive transverse members 15, 16 and 17. The members 15, 16, and 17 are preferably provided about 9 feet apart. 40

Below the rails 2, 3, and 4 slide plates 27, 45 28, and 29 are provided on the cross-ties 10. An example of a rail joint is shown in Fig. 4. As shown it consists exclusively of a pair of fish plates 30 provided one at each side of the rails, the object of the said fish plates being to hold the rail ends in their proper 50 positions relatively to each other, while the rigidity of the rails is assured by the transverse members 15, 16, and 17.

If it is desired to shift the track by means of a shifting machine from the position shown in Fig. 1 in the direction of the arrow shown in the said figure, the said shifting machine is placed on the rails 8 and 9 which are rigidly secured to the cross-ties. When the said machine grasps and lifts the said rails, the rails 2, 3, and 4 which are loose on the cross-ties can slide on their plates 27, 28, 55 50 and 29 without injuring the cross-ties.

By reason of the plates 24 and 25 which connect the transverse members 15, 16, and 17 and which are secured at each end by a single screw forming a pivot, the said joint 60 65 permits of a certain flexibility, so that when

lifting the rails 8 and 9 the track assumes a position which has been shown in an exaggerated way in Fig. 5. Therefore only a portion of the entire weight of the track portion (including the sleepers 10) lifted by 70 the machine will rest on the machine, since the ends of these sleepers or at least the left hand ends thereof are supported on the ground, so that the work of the machine when shifting the track is reduced as compared to the old construction. Also when shifting the rails by hand the same advantages are availed of by the new construction, in which case blocks are placed on the ground under the rails 2 and 4 and in some 75 80 cases also under the rail 3, so that the sleepers 10 are relieved of the weight of the said rails.

A further advantage of my improved construction resides in the fact, that the maintenance cost of the track is reduced. In tracks of the old construction accidents and derailments of the dredging machine were of frequent occurrence, because the rails 2 which in the operation of the machine are 85 subject to high strain became loose on the sleepers and the attendants did not notice this in time, and much time was necessary to repair the plant. But in my improved track derailments will not occur for these 90 reasons. Instead of the expensive rail joints which are necessary in the tracks of the old construction a joint can be provided which is simple in construction, because the connection between the rails by the transverse members 15, 16, 17, 24, and 25 is sufficient. Therefore the cost of the rail joints is reduced to a minimum, which is so much the more important, because in the old construction the joints are subject to injury by 95 100 reason of the rigid construction. In my improved track simple flat plates are sufficient, and thereby the axles of the dredging machine can easily be exchanged by loosening the said simple joints and temporarily 105 removing some of the rails. For this purpose only a few screws must be loosened. Finally the construction of the track can easily be changed and the whole track removed, because all the parts can easily be 110 115 disconnected and re-assembled.

I claim herein as my invention:

1. A track comprising a plurality of rails located one beside the other, common sleepers for all the rails, only a part of said rails 120 being secured to said sleepers and the other ones being loosely supported thereon, and transverse members connecting the loosely supported rails with the rails which are secured to the sleepers.

2. A track comprising a plurality of rails located one beside the other, common sleepers for all the rails, only a part of said rails being secured to said sleepers and the other ones being loosely supported thereon, and 125 130

transverse linked members connecting the loosely supported rails with the rails which are secured to the sleepers.

3. A track comprising a plurality of rails located one beside the other, common sleepers for all the rails, only a part of said rails being secured to said sleepers and the other ones being loosely supported thereon, slide plates secured to the sleepers in positions for supporting the loosely supported rails, and

transverse members connecting the loosely supported rails with the rails which are secured to the sleepers.

In testimony whereof, I have signed this specification in the presence of two subscribing witnesses.

ANDREAS LANGE.
